schaft, Berlin-Tempelhof, Germany, a com-
pany

Application February 1, 1932, Serial No. 590,213
In Germany January 31, 1931

4 Claims. (Cl. 250—20)

(Granted under the provisions of sec. 14, act of
March 2, 1927; 357 O. G. 5)

This invention relates generally to ultra short wave receiving systems, and it relates more particularly to a heterodyne method of ultra short wave reception.

The desirability of applying the heterodyne principle to the reception of ultra short waves has long been recognized, for this application would permit the received high frequency waves to be transformed into alternating current of a lower frequency, the "beat frequency," which can be more efficiently amplified. It has been found, however, that the desired application is by no means easily effected because of the difficulty in maintaining a constant beat frequency. This difficulty has been caused by the fact that the oscillations emitted by the transmitter, as well as the oscillations generated by the heterodyne local oscillators, vary considerably at the high frequencies employed in ultra short wave transmission.

In order to maintain the beat frequencies constant, heterodyne local oscillators controlled by quartz crystal oscillators have been employed. Receivers of this kind, however, being very costly and having a very critical adjustment point, are unsuitable for general use.

According to the present invention, heterodyne methods can be applied to the reception of ultra short waves without the use of quartz crystal oscillators to control the heterodyne local oscillators.

This result is accomplished by employing means for maintaining the oscillations of the local heterodyne oscillators as constant as possible, and then providing means which permit the frequency of the oscillations emitted by the transmitter, as well as the frequency of the oscillations generated by the local heterodyne oscillator, to vary within rather wide limits and yet control a receiver.

An embodiment of the invention is shown by way of example in the accompanying drawing, in which

Fig. 1 illustrates schematically the circuits of the embodiment; and

Fig. 2 is a diagram illustrating the range of permitted frequency variations.

Referring to Fig. 1, D is a dipole antenna which is adapted to receive the ultra-short waves and possesses a coil L₁ which is coupled with the coil L₂ of a receiver. The receiver is provided with a tube R₁ which is connected as an audion valve for the ultra-short wave reception, and has the coil L₂ connected in the grid circuit thereof. Coil L₃ which is connected in the anode circuit

of the tube R₁ serves as a reaction coil and is coupled with coil L₂. Condensers C₁ and C₂ are adapted to tune to the desired receiving frequency. Furthermore, a coil L₄, being coupled with another coil L₅, is disposed in the grid circuit of the tube R₁. The coil L₅ is disposed in the anode circuit of the tube R₂. The tube R₂ is actuating as a heterodyne local oscillator and its grid circuit is provided with an oscillatory circuit L₆, C₃ tuned to the heterodyne frequency, while the anode circuit of the tube with the coil L₅ and the condenser C₄ is likewise tuned to the desired frequency. In the anode circuit of the tube R₁ a beat or intermediate frequency *zf* is produced by heterodyning the transmission frequency received over the dipole to the frequency produced by the heterodyne local oscillator R₂, the beat or intermediate frequency being led to an intermediate frequency amplifier Z over the transformer T₁.

The intermediate frequency amplifier Z is of a well known construction. For this purpose all customary types of intermediate frequency amplifiers, be it with transformer or resistance coupling, etc., may be used. An amplifier according to Fig. 1, for instance, may be used wherein in the input of the first tube R₃ a choke filter C₅, L₇, C₆, L₈ and a condenser filter L₉, C₇, L₁₀, C₈ are employed. In the anode circuit of the tube R₄ is disposed a circuit S₁ tuned to the intermediate frequency and coupled with a circuit S₂ which is likewise tuned to the intermediate frequency and disposed in the grid circuit of a second tube R₄. The anode circuit of this second tube is then connected to the transformer T₂, the secondary winding of which is connected with the low frequency section N, of a generally accepted type. In the form illustrated in Fig. 1 the low frequency section N contains a detector R₅ upon the input of which intermediate frequency from transformer T₂ is impressed. The low frequency signal detected in the detector R₅ is impressed through transformer T₃ upon the input of an amplifier R₆ which amplifies the detected signal and impresses it upon the receiver E, rendering the received signals audible.

In order to maintain the intermediate frequency as nearly constant as possible, it is desirable to heat the filaments of the tubes R₁ and R₂ indirectly rather than directly, for it is well known that, owing to the thermal inertia of an indirectly heated filament, the emission of a tube having a filament of this type is influenced to a lesser degree by fluctuations in the heating of its fila-

ment than is the emission of a tube having a directly heated filament.

The potentiometer G, which is of the glow discharge tube type, is a further means for maintaining the frequency of the tubes R₁ and R₂ constant. Since the frequency generated by each of these tubes depends largely upon their anode potential, it is essential to keep this potential constant which is done by means of the potentiometer G. Since potentiometers of this type are well known in the art, it is regarded as unnecessary to describe its operation in detail here.

Despite the indirect heating of the filament in the tubes R₁ and R₂ and the use of the potentiometer G to control the anode potential in these tubes, there is necessarily some variation in the intermediate frequency zf impressed upon the intermediate frequency amplifier Z. This variation is caused by variations in the frequencies of the signals received by the antenna D and residual variations in the frequencies of the oscillations generated by the local oscillator 2. These frequency variations result from the ultra high frequencies of the transmitted signals and of the locally generated oscillations, respectively.

The variations of the intermediate frequency, however, have no effect upon reception provided they are within certain limits, for the intermediate frequency amplifier Z includes, among its circuit elements, one or more band pass filters which are so designed that the total amplification of this amplifier is substantially the same for a wide band of frequencies, as indicated at B in Fig. 2. The amplifier Z may also include several stages of amplification for the purpose of intensifying the intermediate frequency zf .

Referring to Fig. 2, S represents the transmission band of the distant transmitter; the continuous curve in S represents the relative amplitude of the intermediate carrier frequency f_0 and the side bands thereof; and, as before stated, B represents the transmission band or frequency range f_1 to f_2 of the band pass filter or filters in the intermediate frequency amplifier Z. The intermediate carrier frequency f_0 lies within the range f_1 to f_2 which is so chosen that the signalling band S composed of the intermediate frequency carrier f_0 with the upper and lower side bands, may shift its position, to some extent, and still be within the transmission range f_1 to f_2 of the intermediate frequency amplifier. Usually the width of the signalling band S, when both side bands are transmitted, is not more than 20,000 cycles with a modulating signal composed of frequencies up to 10,000. It should be noted that the transmission band of the band pass filters is a multiple of the transmission band of the distant transmitter, and may be of any selected width. For example, in the case of a transmitter modulated in a normal manner, the band pass filters of the intermediate frequency amplifier Z may have a transmission band of 100,000 cycles per second. It is evident from Fig. 2 that considerable variations in the frequency band of the transmitter (not shown) and in the frequency of the oscillations generated by the tube R₂ may occur, yet, so long as the resultant intermediate or beat frequency zf varies within the limits of B, the total amplification of the intermediate frequency amplifier Z remains substantially the same.

Hence, if the oscillations of the receiver tubes R₁ and R₂ are maintained as nearly constant as possible by indirectly heating the filaments of these tubes and associating a potentiometer of the

glow discharge type with the anodes thereof, and the transmission band of the intermediate frequency amplifier Z is made sufficiently broad to pass the beat or intermediate frequency despite any fluctuations in the oscillations generated by the transmitter (not shown) and by the tube R₂, then ultra short waves may be detected and received in a most reliable manner without the use of a quartz crystal oscillator for controlling the local oscillator at the receiver.

10

It is to be understood that the invention is not restricted to arrangements for separate local oscillators such as R₂, but may be also employed with self heterodyne local oscillators. It is evident, also, that modifications of the invention may be made within the scope indicated by the appended claims without departing from the spirit of the invention.

15

What is claimed is:

1. The method of ultrashort wave reception which comprises receiving transmitted modulated ultrashort waves of variable frequency, combining locally generated oscillations of variable frequency with the carrier frequency of the received waves to produce an intermediate frequency, conducting the intermediate frequency through a path having an intermediate frequency transmission band equal to a multiple of the transmitted frequency band, and utilizing the intermediate frequency so conducted to produce a signal.

20

2. In a high frequency receiver, an antenna for receiving ultrashort waves, an ultrashort wave detector tube associated with said antenna and having an anode and an indirectly heated filament, a local oscillator tube also having an anode and an indirectly heated filament, a glow discharge potentiometer for controlling the anode potential of said tubes, means for impressing said locally produced oscillations upon said detector tube for interaction thereon with the received oscillations to produce an intermediate frequency, and a receiving circuit for the intermediate frequency, said receiving circuit having an intermediate transmission frequency band equal to a multiple of the frequency band of the ultrashort waves received by said antenna.

35

3. In a high frequency receiver, an antenna for receiving ultrashort waves, an ultrashort wave detector associated with said antenna and having an anode and an indirectly heated filament, a local oscillator also having an anode and an indirectly heated filament, a glow discharge potentiometer for controlling the anode potential of said detector and oscillator, means for impressing said locally produced oscillations upon said detector tube for interaction thereon with the received oscillations to produce an intermediate frequency, an amplifier for the intermediate frequency, means whereby the total amplification of said amplifier is substantially the same for a wide band of frequencies, and receiving means associated with the output of said amplifier.

40

4. In a high frequency superheterodyne receiver, the combination of a first detector and a heating frequency oscillation generator employing tubes of the indirectly heated type, each tube having a plate circuit, means coupling the oscillator to the detector for impressing thereon the generated oscillations, a source of current for the plate circuits of said tubes, a glow discharge potentiometer connected in parallel with said source, and leads from said potentiometer to the plates of said tubes.
